METHOD OF AND MACHINE FOR FORMING METAL PLATES

Application filed November 19, 1931. Serial No. 576,054.

This invention relates to a method of forming metal plates, and has reference more particularly to a method of forming continuous and noncontinuous ribs in a metal sheet. The invention also relates to a machine suitable for carrying out the above described method.

This application is a continuation in part of an application by the same inventors, 10 Serial No. 562,522, filed September 12, 1931, entitled "Roof and floor construction". In this copending application is disclosed a plate having longitudinal continuous and non-continuous grooves or channels for the 15 purpose of forming a roof deck having great longitudinal strength, and a method of manufacturing this roof deck was disclosed. The present application deals more specifically with this method of manufacture of 20 the roof deck or any type of corrugated plate, and discloses in detail a machine suitable for carrying out the method.

While the method and machine disclosed in the present application is suitable for use 25 on a wide variety of sheet-metal products, or products of a non-metallic nature, it is especially useful in forming the metal roof deck disclosed in the aforementioned copending application. This roof deck is composed 30 of a metal sheet in which is formed a plurality of continuous, longitudinal grooves or channels and between the continuous channels are located non-continuous channels or 35 grooves so arranged as to permit overlapping of the roof deck plates as they are supported upon the framework of the roof. It 40 is desirable to form the roof deck plates continuously and to accomplish the method with the machine disclosed in such a way 45 that the non-continuous channels are formed at about the same time that the continuous channels are formed.

An object of this invention, therefore, is to provide a method of forming continuous 45 and non-continuous grooves or channels in a metal sheet.

Another object of the invention is to provide an apparatus for accomplishing the method, in which the movement of the forming 50 rolls for the non-continuous channels

is controlled automatically; also to improve methods of and machines for corrugating sheet material in other respects hereinafter specified and claimed.

Reference is to be had to the accompanying drawings forming a part of this specification, in which

Fig. 1 is a perspective view of a roof deck made according to our improved method and machine,

Fig. 2 is a side elevation of the corrugating machine,

Fig. 3 is a sectional view through the machine taken on line 3—3 of Fig. 2,

Fig. 4 is a side elevation of the delivery end of the machine with parts broken away to disclose the construction,

Fig. 5 is a transverse sectional view through the machine taken on line 5—5 of Fig. 4,

Fig. 6 is a sectional elevation through the machine taken on line 6—6 of Fig. 4, and

Fig. 7 is an elevation of a portion of the mechanism looking in the direction of line 7—7 of Fig. 5.

As disclosed in our aforementioned copending application, our improved roof deck comprises a metal plate 10, which is preferably composed of steel but may be of any other suitable metal. A plurality of channels 11 are formed in said plate in spaced parallel relation, said channels being preferably few in number and spaced comparatively far apart so as to provide a deck plate surface 12 in which the distance between channels is great compared to the width of the channels. The centers of the channels 11 are preferably equi-distant the entire length of the plate 10. These channels have upwardly extending legs 13 which are substantially parallel adjacent one end of the deck plate 12, said legs flaring only slightly outwardly to permit satisfactory rolling during the fabrication of said plate.

After the channels 11 have been rolled with substantially parallel sides 13, the ribs or channels 14 are rolled in substantially the center of each of the plate surfaces 12, said ribs extending from one extreme end of the plate to a point materially short of 100

the opposite end of the plate 10. The rib 14 serves the purposes of drawing together the legs 13 of adjacent channels so that said legs flare upwardly at a substantial angle 5 to the vertical, thus permitting the parallel legs of the adjoining plate to telescope slightly into the flared legs of a deck plate with the overlapping deck plate surfaces 12 in face to face abutting relation. The ribs 10 14 also serve to give longitudinal stiffness and strength to the entire deck plate construction. By actual test, we have found that these ribs 14 make the deck plate in excess of 10% stronger than it is without 15 the formation of said ribs 14.

One edge of the deck plate 10 is provided with a downwardly extending flange 15, and the opposite edge of said plate is provided with a downwardly extending L-shaped 20 channel 16. The flange 15 of one deck plate is adapted to engage in or interlock with the L-shaped channel 16 of the adjoining deck plate. Suitable clips are provided for attaching the deck plates to the supporting 25 framework or purlins, as has been more fully described in said copending application.

The sheets of metal to be corrugated or formed into roof plates or other desired articles of manufacture, are placed upon a 30 table 17 between longitudinal guides 18, and are advanced between an upper roll 19 and a lower roll 20 of a rolling machine having side frames 21 supported on standards 22. Several pairs of these rolls similar to the rolls 19 and 20 are required 35 as seen in Fig. 2, the pairs of rolls differing slightly in shape so as to gradually form the plate with channels 11 and 16 and the flange 15. Power for turning the rolls 19 and 20 and the following pairs of rolls is 40 supplied from a motor 22a connected to a speed reducer 23. A chain 24 connects the speed reducer 23 to a sprocket wheel 25 secured to a shaft 26 which runs longitudinal- 45 ly the full length of the machine. A series of bevel gears 27 are secured to the shafts 29 which carry the rolls 20. Suitable screws 30 are provided with adjusting hand-wheels 31, so that the pressure between the 50 rolls 19 and 20 can be easily adjusted to give the proper forming action on the metal sheet.

One of the salient features of our invention resides in the forming of the non- 55 continuous grooves or channels 14 in the deck plate 12. In order to form these grooves, a pair of rolls 33 and 34 is provided, the latter being movable substantially vertically so as to move into and out of engagement with the moving metal plate. The roll 33 is provided with annular grooves 35, and the roll 34 is provided with annular shoulders 36 for engaging in the grooves 35. The engagement of the shoulders 36 60 with the deck plate, forces said plate down-

wardly into the grooves 35 to form the channels 14. Annular shoulders 37 formed on roll 34 engage the channels 11 previously formed in the plate 12, so as to accurately position the plate 12 relative to the shoulders 36. The roll 33 is provided with annular grooves 38, which register with the annular flanges 37.

The roll 33 is keyed onto a shaft 39 and the roll 34 onto a shaft 40. Each of the shafts 39 and 40 is provided with an annular shoulder 41 and a spacing collar 42 extending between said shoulder 41 and each of the rolls. Lock-nuts 43 are provided on each of the shafts 39 and 40 to rigidly position the rolls 33 and 34 on their shafts with the forming shoulders and grooves in accurate registry position. The shaft 39 is rotatably and rigidly supported in stationary bearings 44, 45 and 46, which are preferably of the ball-bearing type and are mounted in suitable cast framework 47 which serves to support the moving parts of the machine. A bevel gear 48 is provided on the end of shaft 39 and engages with a bevel gear 49 on the longitudinal shaft 26 so as to accomplish the continuous rotation of shaft 39 and roll 33 at the exact speed of the deck plate.

In order to accomplish the substantially vertical movement of the shaft 40, relative to the shaft 39, one end of said shaft 40 is rotatably mounted in vertically movable bearings 50 and 51, each of which is supported by a bifurcated bell-crank lever 52, between the arms of which is positioned a spur gear 53 which is rigidly secured to the shaft 40. Two arms 54 of the lever 52 extend rearwardly of the machine and are pivotally mounted upon a shaft 55 by means of bearings 56, one being provided for each of said arms 54. The ends of shaft 55 are rigidly mounted in the walls of the machine housing 57, and a spur gear 58 is secured to said shaft between the lever arms 54. The gear 58 meshes with the gear 53 and also meshes with an idler spur gear 59, which in turn meshes with a spur gear 60 which is rigidly secured on the shaft 39. The end of the shaft 40 opposite the bearings 50 and 51 is rotatably mounted in a bearing 62 which is formed intermediate the ends of a bell-crank lever 63. One end of the lever 63 is pivotally mounted by means of pin 64 to a rigid bracket 65, the latter also serving to support the bearing 46 for shaft 39.

In order to accomplish the substantially vertical movement of the shaft 40, relative to the shaft 39, a cam shaft 67 is rotatably mounted in bearings 68 which are formed on bearing brackets 69, the latter being secured by bolts 70 to the framework of the machine. A bearing bracket 71 also serves to support the outer end of shaft 67. A

pair of cams 72 and 73 are secured to the shaft 67 adjacent the bearings 68, said cams engaging with rollers 74 and 75 respectively. The roller 74 is mounted upon the outer 5 end of a lever 76 and the roller 75 is mounted upon the outer end of a similar lever 87 on the opposite side of the machine. The end of the lever 76 opposite the roller 74 is pivotally secured by means of pin 77 10 to a bracket 78. A rod 79 is pivotally connected by means of pin 80 to the lever 76 intermediate its ends, and the upper end of the rod 79 is pivotally secured by means of pin 81 to the free end of lever 52. The 15 rod 79 passes loosely upwardly through a bottom 82 formed on the housing 57, and a spring 83 is mounted on the rod 79 between a nut 84 on said rod and the bottom 82, so as to urge the rod 79 and lever 76 upwardly 20 to maintain the roller 74 in contact with the cam 72. A similar rod 85 is positioned on the opposite side of the machine, being pivotally connected at its upper end to the lever 63 by means of pin 86. The 25 lower end of rod 85 is pivotally connected to a lever 87 similar to lever 76.

Since the vertical position of the lever fulcrum pin 77 determines the position of the roll 34 with respect to the roll 33, it is desirable 30 to have means for vertically adjusting the fulcrum pin 77. For this purpose, we provide the bracket 78 with a face in sliding contact with a slide way 89 formed on a bracket 90. A screw 91 is rotatably 35 mounted in a vertical position in the bracket 90, and shoulder 92 formed on the bracket 78 is threaded to receive the screw 91. The upper end of the screw 91 is provided with a worm wheel 93 which meshes with a worm 40 94 secured to a shaft 95, the latter being provided with a hand-wheel 96 for manually adjusting the vertical position of the pin 77.

The shaft 67 is caused to rotate intermittently 45 for a single revolution, so as to cause the non-continuous channels 14 to be formed in the deck plate. For rotating the shaft 67, a spur gear 98 is secured to the outer end of a shaft 99 which is rotatably mounted in bearings 100, 101 and 102 secured to the framework of the machine. A bevel gear 103 is secured to the shaft 99 and meshes with a bevel gear 104a on the forward end 50 of longitudinal shaft 26. An idler spur gear 104 is rotatably mounted upon a stub shaft 105, secured to the framework of the machine. The gear 104 meshes with a spur gear 106, which in turn is secured to a sleeve 107 mounted for rotary movement on the 55 shaft 67.

A clutch disc 109 is operated by toggle arms 110 from a collar 111. Ears 112 are secured to the collar 111 and a ring 113 embraces the collar 111, having outstanding 60 integral pins 114 for receiving the ends of

push rods 115. A collar 116 is rigidly secured to the shaft 67, and a compression spring 117 is mounted upon the shaft 67 between the collar 116 and a collar 118. Outstanding ears 119 are formed on the 70 collar 118 for receiving the ends of rods 115, said rods being threaded to receive locking nuts 120. The clutch disc 109 and the collars 111 and 118 are secured to the shaft 67 by means of feather keys so as to 75 have free sliding movement on said shaft. The spring 117 normally tends to hold the clutch disc 109 out of engagement with the clutch drum 108 so that shaft 67 does not rotate. 80

A bell-crank lever is pivoted on a pin 121, said pin being secured to a bracket 122. One arm 123 of said lever extends downwardly and engages against the annular surface of the collar 118. A counter-clockwise 85 movement of the bell-crank lever, as seen in Fig. 3, causes the lever arm 123 to move the collar 118 to the right, so that a shoulder 124 on said collar 118 rides up on an annular shoulder 125 formed on the bracket 122, thus 90 causing clutch disc 109 to engage the clutch drum 108 and rotate the shaft 67 through one revolution, after which the shoulder 124 again drops into place, thereby releasing 95 the clutch. 100

A second arm 126 of the bell-crank lever is pivotally connected by a rod 127 to a spring not shown contained in a spring cylinder 128, the latter being pivotally anchored at one end to a rod 129 secured to the framework of the machine or other fixed point. Thus the spring and cylinder 128 normally tend to move the lever arm 126 in a counter-clockwise direction as seen in Fig. 3, against the action of spring 117. 105

A catch 130 is pivotally mounted on pin 131 secured to bracket 122, said catch normally tending to engage behind a shoulder 132 formed on a lever 133. The lever 133 is pivotally mounted on a pin 134 secured to the bracket 122, and an arcuate connecting link 135 is pivotally connected to the catch 130 and the lever arm 126, said link tending to cause the catch 130 to follow the movements of lever arm 126. A flat spring 137 is secured at one end to the bracket 122 and presses downwardly on top of the catch arm 133 so as to securely hold the catch 130 in locked position. 110

As the metal plates emerge from the machine, they pass along a table 138 until the forward end of the plate strikes against an electrical switch arm 139 which closes the circuit 140 and energizes a solenoid 141. An armature 142 inside said solenoid is then 115 lifted when the solenoid is energized and a rod 143 suspended from said armature has an outstanding shoulder 144 formed on its lower end, which engages with the downwardly extending end of catch arm 133 120 125 130

so as to lift said catch arm and release the catch 130 from catch shoulder 132, thus permitting the lever arm 126 to swing downwardly in a counter-clockwise direction as seen in Fig. 3, until a roller 145, rotatably mounted on said lever arm 126, engages with a cam 146 which is rigidly secured on the outer end of shaft 67. The downward movement of lever arm 126 is also limited by a stop 147. As the lever arm 126 swings downwardly, the clutch is engaged and shaft 67 makes one complete revolution until the large diameter section on said cam 146 again raises the lever arm 126 so that catch 130 again engages behind catch shoulder 132 ready for a new cycle of operation. When the solenoid is released, the armature 142 moves downwardly so that a shoulder 148 formed on the rod 143 rests upon a flat leaf spring 149 which is secured to a bracket 150.

In order to iron out the metal plate after the corrugations are complete and insure that the surface of said plate is smooth and even, an ironing roll 151 is mounted securely upon the shaft 99 in the same general manner that the roll 33 is mounted upon the shaft 39. A co-operating ironing roll 152 is mounted upon a shaft 153 which is rotatably supported in bearings 154, 155 and 156, these bearings being arranged for vertical adjustment by means of adjusting screws 157, 158 and 159 respectively, so that the pressure of the rolls upon the metal plate can be accurately adjusted.

It is desirable that the location of the switch 139 be adjustable so that the length of the non-continuous channel 14 can be accurately set. For this reason, the switch arm 139 is pivotally supported upon a bracket 162 by a pin 163. The bracket 162 has a collar 164 which is slidably mounted upon a bar 165. The collar 164 is provided with a catch handle 166 so that a catch 167 will engage suitable recesses in the upper surface of the bar 165, thus permitting the collar 164 to be located in any desired position along said bar 165. In order to give a micrometer or fine adjustment of the position of the switch arm 139, the bar 165 is slidably mounted in a pair of bearings 168 and 169. A bracket 170 is associated with the bearing 169 and has an outstanding flange 171 for receiving a micrometer adjusting screw 172. The section of the bar 165 extending beyond the bearing 169 is graduated and a pointer 173 on the bracket 170 indicates the position of the bar 165 and switch arm 139.

In the operation of the machine, the flat metal plates to be formed into shape are moved manually along the table 17 between the guides 18 until the plate is gripped between the first pair of forming rolls 19 and 20. These rolls and subsequent forming rolls are caused to rotate continuously by a

motor 22a operating through speed reducer 23, chain 24, shaft 26 and bevel gears 27 and 28. The first ten pairs of forming rolls shown in Fig. 2 serve to form the continuous channels 11 and 16 and the flange 15 in the plate.

For forming the non-continuous channels 14 in the plate, as the plate moves outwardly from the last pair of continuous forming rolls, it passes between the non-continuous forming rolls 33 and 34 with the cams 72 and 73 in the position shown in Fig. 4 in which the large radius section of the cams press the levers 76 and 87 downwardly against the action of springs 83 so that said rolls 33 and 34 firmly grip the plate and form the non-continuous grooves or channels 14. The plate passes between ironing rolls 151 and 152 which serve to straighten out any irregularities existing in the plate and then the forward end of the plate engages switch arm 139.

The actuation of switch arm 139 serves to close the electric current 140 and actuates the solenoid 141 so as to raise the solenoid armature 142 and rod 143. The raising of shoulder 144 releases the catch lever 133 so that catch 130 is disengaged from the catch shoulder 132 and lever 126 swings downwardly under the action of a spring in spring cylinder 128 so that roller 145 engages the cam 146. At the same time the lever arm 123 pushes the collar 118 to the right as seen in Fig. 3, thus causing the clutch disc 109 to engage the clutch drum 108. The clutch drum 108 has been continuously rotated with its sleeve 107 to which is secured the spur gear 106 meshing with idler gear 104, which in turn meshes with gear 98 on the end of driven shaft 99. The actuation of the clutch 109 causes the shaft 67 to rotate so that the rollers 74 and 75 engage the small radius section of the cams 72 and 73, respectively, and the forming roll 152 is moved upwardly by the action of springs 83 on the levers 52 and 63. The cams 72 and 73 are so shaped that the raising of levers 76 and 87 and forming roll 152 occurs gradually so that the end of the discontinuous channels 14 gradually taper off into the flat deck plate 12, leaving the end of the deck plate in a flat condition so that overlapping of the deck plate in roof construction is possible. Upon the continued rotation of shaft 67, the shoulder 124 again drops into position in the recess in the bracket 125 so that the clutch is released and at the same time the large radius section of cam 146 engages the roller 145 and raises the lever 126 and catch lever 130 so that the latter engages behind the catch shoulder 132 ready for a new cycle of operation.

The pressure of the forming rolls 19 and 20 is adjusted by means of hand-wheels 31 and the pressure between the ironing rolls

151 and 152 is adjusted by means of screws 157, 158 and 159. The location of the fulcrum pins 77 of levers 76 and 87, and therefore the pressure of the non-continuous roll 5 34 on roll 33, is adjusted by means of hand-wheels 96. The position of the switch arm 139 is regulated by actuating the catch lever 166 and moving the collar 164 along the bar 165 to the desired position. A micrometer 10 adjustment of the switch arm 139 is secured by sliding the bar 165 axially through the bearings 168 and 169 by means of micrometer screw 172.

We would state in conclusion that while 15 the illustrated example constitutes a practical embodiment of our invention, we do not wish to limit ourselves precisely to these details, since manifestly, the same may be considerably varied without departing from 20 the spirit of the invention as defined in the appended claims.

Having thus described our invention, we 25 claim as new and desire to secure by Letters Patent:—

25 1. The method of forming a roof deck plate, comprising the formation of a plurality of spaced parallel channels therein coextensive with the length thereof, then forming ribs in said plate intermediate said channels and extending from one end of the plate but terminating short of the opposite end thereof, thereby spreading the sides of said channels in the ribbed portion of the plate.

35 2. The method of forming a roof deck plate comprising the formation of a plurality of spaced parallel channels therein coextensive with the length thereof, and having substantially parallel sides, then forming 40 ribs in said plate intermediate said channels and extending from one end of the plate but terminating short of the opposite end thereof to cause the sides of the channels in the ribbed portion of the plate to flare.

45 3. The method of forming a roof deck plate, comprising the formation of a plurality of spaced parallel channels therein coextensive with the length thereof and having 50 substantially parallel sides, said channels being so spaced that the width of the plate between adjacent channels will be materially greater than the width of each channel, then forming a relatively shallow rib in said plate intermediate said channels and 55 extending from one end of the plate but terminating short of the opposite end thereof, to cause the sides of the channels in the ribbed portion of the plate to flare.

60 4. The method of making a roof and floor plate, which comprises rolling flanges on the edges of said plate and longitudinal channels in the body of said plate, said channels having substantially parallel sides, and then 65 rolling longitudinal ribs in said plate between said channels by a roll which inter-

mittently engages said plate so that said ribs extend a distance less than the full length of said plate, said ribs serving to bend the sides of said channel out of parallel relation to permit overlapping of said 70 plates.

5. The method of forming a plate with channels which comprises forming a plurality of spaced parallel channels coextensive with the length thereof, and forming 75 ribs in said plate intermediate said channels and extending from one end of the plate but terminating short of the opposite end thereof.

6. In a machine for forming metal plates, means for moving said plates along a predetermined path, rolls for forming non-continuous ribs in said plates, a switch arm positioned in the path of travel of said plates, and means associated with said 80 switch arm for controlling the intermittent engagement of said rolls with said plates.

7. In a machine for forming metal plates, a pair of rolls for rolling non-continuous channels in said plates during the 90 continuous movement thereof, and means controlled by the movement of the plates to move one of said rolls away from the other of said rolls so as to discontinue the forming action of said rolls on said plates.

8. In a machine for forming metal plates, means for moving said plates along a predetermined path, a pair of non-continuous forming rolls arranged to intermittently engage a plate so as to roll a non-continuous channel in the face thereof, a lever for moving one of said rolls relative to the other of said rolls, cam means for actuating said lever, a shaft for rotating said cam, and a one-revolution clutch controlled by the movement of said plate for rotating said shaft and said cam intermittently.

9. In a machine for forming plates, means for moving a plate along a predetermined path, a pair of forming rolls for rolling channels in said plate, cam means for causing the separation of said rolls in order to form channels in said plate less than the full length of said plate, and means for automatically actuating said cam at predetermined intervals.

10. In a machine for forming metal plates, means for moving a plate along a predetermined path, a pair of forming rolls arranged to form a non-continuous channel in said plate, a lever for separating said rolls so that the channels in said plate extend less than the full length of said plate, and means for automatically actuating said lever at predetermined intervals.

11. In a machine for forming metal plates, means for moving a plate along a predetermined path, a pair of forming rolls arranged to operate upon said plate so as to form a non-continuous channel in said 130

plate, a solenoid associated with said rolls, means associated with said rolls for actuation of said solenoid at predetermined intervals depending upon the movement of 5 said plate, and means associated with said solenoid to separate said rolls when said solenoid is actuated.

FRED A. MANSKE.
